OSCAR SANDBERG, OF SÖDERTELJE, SWEDEN, ASSIGNOR TO AKTIEBOLAGET SVENSKA TOBAKSMONOPOLET, OF STOCKHOLM, SWEDEN.

MACHINE FOR MANUFACTURING MOUTHPIECES FOR CIGARETTE-CASINGS.

1,277,132.

Specification of Letters Patent. Patented Aug. 27, 1918.

Application filed April 3, 1917. Serial No. 159,395.

To all whom it may concern:

Be it known that I, OSCAR SANDBERG, a subject of the Emperor of Russia and citizen of Finland, residing at Södertelje, in the county of Stockholm and Kingdom of Sweden, have invented new and useful Improvements in Machines for Manufacturing Mouthpieces for Cigarette-Casings, of which the following is a specification.

10 This invention relates to machines for manufacture of mouthpieces for cigarette casings or cigarette tubes. One object of this invention is to provide a machine suited for a rather high producing capacity, so that the number of pieces completed in the time unit will considerably exceed those manufactured by hitherto known machines. Another object of this invention is to reduce the waste of the paper when manufacturing 20 the blanks for the mouthpieces. A further object is to provide mouthpieces suited to allow the tobacco to be forced into the mouthpiece proper a little distance beyond its inner end whereby that rather weak point 25 of the cigarette, that is that point, where the casing leaves the more stiff mouthpiece, is strengthened and accordingly the risk of breakage of the completed cigarette is reduced to a minimum.

30 Attending to the objects mentioned, I manufacture the mouthpieces as hitherto known from a continuous paper strip the width of which equals the length of the completed mouthpiece, which strip I cut off 35 in two different courses, so that the cuts are alternately square and oblique. The forward end of every alternate cut off piece consequently will be square, and these pieces I then give a rearward motion in relation to 40 the other cut off pieces, the forward end of which attains an oblique shape, and after that I cause the two cut off pieces, which as mentioned move in opposite directions, to be rolled up simultaneously to form mouth- 45 pieces. After that, I introduce the two mouthpieces alongside one another each into a cigarette casing, which casings have been manufactured by a separated machine and supplied to this mouthpiece machine, and 50 finally I force the tapered inner end of the rolled mouthpiece paper strip slightly rearwardly into the casing thus procuring at this end of the mouthpiece a small space where the tobacco, when introduced in the

casing, can enter the mouthpiece proper so far till it gets stopped up by the impressed paper end.

In the accompanying drawings:

Figure 1 is a view showing in side elevation and partly in section the improved machine in one working position.

Fig. 2 is a plan view of the machine in the same position.

Fig. 3 is the same view as in Fig. 1 but in another working position. 65

Fig. 4 is a plan view of the machine in the last mentioned working position.

Fig. 5 is a cross section of the machine on the line A—A of Fig. 2.

Fig. 6 is a view looking from the right hand of Fig. 1. 70

Fig. 7 is an end view of the feeding device.

Fig. 8 is a side view of the same parts.

Fig. 9 is a side view of a support for the 75 paper strip.

Fig. 10 is a side view of the moving and retarding device for the parts, which serve to revolve the cut off paper piece.

Fig. 11 is a plan view of last mentioned 80 parts.

Fig. 12 is an elevation of a clamping device for the cigarette casings when placing the mouth piece thereon.

Fig. 13 is a side view of the same parts. 85

Fig. 14 demonstrates the completing operation of the mouthpiece when applied on the cigarette casing.

Fig. 15 is an end view of the cigarette casing with completed mouthpiece. 90

Fig. 16 is a vertical section, on an enlarged scale, of the rolling needle with mouthpiece, before applying same on the cigarette casing.

Fig. 17 is an end view of the rolling needle with the sleeve. 95

Fig. 18 is the same view as in Fig. 16 but illustrating how the mouthpiece is inserted into the cigarette casing.

Fig. 19 is a plan view of the two rolling 100 needles.

Fig. 20 an end view of these needles in section.

Figs. 21-24 show diagrammatically several positions of the feeding device. 105

Fig. 25 demonstrates diagrammatically eight different stages in the motion of the paper strip.

Fig. 26 is an enlarged detailed view showing in vertical section one form of bridge embodying my invention.

Fig. 27 is a transverse sectional view of the bridge shown in Fig. 26.

Fig. 28 is a plan view, partly in section, of the bridge shown in Figs. 26 and 27.

The same reference letters indicate similar parts throughout all the figures.

- 10 The continuous paper strip 1 is fed along by means of two feeding rollers 2 and 3 of which the lower roller 2 is keyed on a rotatable shaft 4, while the upper roller 3 by means of journals 5 is supported in slots 7
 15 directed toward the lower roller 2, so that the upper roller 3 can be slightly moved up and down relatively to the lower roll 2. Spiral springs 8, stretched between the journals 5 and the prongs 9 in support 6 render
 20 the up- and down motion of the roller 3 elastic, so that the pressure from the upper roller 3 can be kept practically constant for varying thicknesses in the paper strip 1. The lower roller 2 has on its circumference
 25 two separate rough parts 10 and 11 of different length and spaced by smooth parts 12, 13 for purposes which will be explained hereinafter.

- 30 In front of the feeding mechanism 2, 3 there is arranged a pair of scissors or knives 14 positioned such, that they cut the paper strips 1 at right angle with reference to the length direction of the strip, and which scissors or knives are put in action in any
 35 known manner, as for instance by means of a cam disk 14^a.

- At a suitable distance from the knives 14 there is located another pair of scissors or knives 15, positioned in an oblique direction
 40 relatively to the length of the paper strip 1 and actuated from a cam disk 15^a. Between the two pairs of scissors 14, 15 there is an up and down movable bridge or table 17 (Fig. 9) actuated from an eccentric 20
 45 on the shaft 19 which shaft is caused to revolve by means of a helical gear 4^a, a transmission shaft 18 and a bevel gear 18^a. The eccentric 20 operates the one arm 21 of a double lever, pivotable on a fulcrum 21^a in
 50 the support 22, the rear arm 23 of which lever actuates the table 17 by means of a link 24. The full lines in Fig. 9 indicate the lower position of the table 17 and its actuating parts and the dot and dash lines the
 55 upper position of same parts.

- In front of the table 17 there is provided in the length direction of the paper strip 1 a bridge 25, pivotable about an axis parallel to the length of the paper strip 1. Figs. 1
 60 and 2 show this bridge 25 in a horizontal position and Figs. 3 and 4 in a vertical position turned 90 degrees about the said turning axis. As shown in Figs. 26, 27 and 28, the bridge 25 is of rectangular formation,
 65 the longitudinal edges of which are pro-

vided with guides 90 secured to the bridge by means of screws 91. The bridge 25 is caused to turn by means of a ratchet device 36^a, 37 actuating a pivot 26 projecting from the one end of the bridge and journaled in 70 a support 27. Said pivot 26 is indirectly operated from the ratchet device 36^a, 37 by means of a toothed gear 38, 38^a, the pinion 38^a of which is positively revolved by the ratchet pawl 36^a, which operates the 75 ratchet wheel 37 that is unmovably united with the pinion 38^a. The ratchet pawl 36^a is carried by a link suspended rod 36, the opposite end of which is attached to a lever 39 pivotable about a fulcrum 39^a on the 80 frame 38. A spring 40^a actuating the link 40 of the rod 36 tends to press the lever 39 against a cam disk 41 on the shaft 18 which cam disk transmits the revolving of shaft 18 on to the lever 39, rod 36, ratchet device 36^a, 85 37, toothed gear 38^a, 38 and bridge 25. To regulate the length of the movements of the rod 36 and consequently the movements of the ratchet mechanism and the bridge 25, the rod 36 is slidably connected with the 90 lever 39 in a slot 42 therein.

The turning about of the bridge 25 is checked by means of a pawl 34, actuated from a lever 30 and coöperating with a disk 28 keyed on the pivot 26 of the bridge 25. 95 Said disk is provided with two diametrically opposed apertures 29 by which the pawl 34, during the revolving of the pivot 26 with the disk 28, alternately can be engaged and thereby prevent any further revolving of the disk and the journal 26 with bridge 25, until the pawl 34 is removed from its engagement with the aperture 29. This removing of the pawl 34 is effected by means of a cam disk 33 on the shaft 19, provided 100 with a projection 35 which coöperates with a roller 32 on the lever 30 in such a way, that the roller 32 through the projection 35 is pushed outward thereby causing the lever 30 to swing to the left hand (Fig. 10) removing the pawl 34 from the aperture 29. A spring 31 keeps the lever 30 with pawl 34 against the plain surface portion of the disk 28, so that the pawl 34 always is prepared to immediately move into the apertures 29, as the one or the other of these two apertures has arrived in front of the pawl 34 during the revolving of the shaft 26. The apertures 29 are so positioned with reference to the bridge 25 that the checking 110 of same by means of the pawl 34 will always occur when the bridge occupies one or the other of its two horizontal positions as illustrated in Figs. 1 and 2.

On each of the horizontal sides of the 125 bridge 25 there are feeding implements, one upper implement 43 and one lower implement 44, both pivotally mounted in a support 45 such, so that they can be revolved in a plane passing through the axis of the 130

- continuous paper strip 1. These implements are each provided with a concentrically curved working surface and are operated with a uniform revolving movement such, that, when their working surfaces pass along the respective sides of the bridge 25, they move in opposite directions with reference to the bridge, viz. the upper implement 43 in the same direction as the feeding direction 10 of the continuous paper strip 1 and the lower implement 44 in the reverse direction thereto. The revolving of these implements is effected by means of toothed gears 46 from the shaft 19.
- 15 Between the table 17 and the bridge 25 and at right angle to the feeding direction of paper strip 1 there are situated two parallel rolling needles 47 and 47^a of some known type and revolved intermittently by 20 means of a toothed wheel 56 from the driving shaft 52 of the machine. The wheel 56 is provided with teeth merely on a portion of its circumference, so that the pinions 56^a on the two rolling needles' shafts revolve 25 only, when this portion of the wheel 56 is engaging with them, but remain at rest during the other portion of the turn of the shaft 52. The rolling needles are each surrounded by a sleeve 48 (Figs. 19, 20) which 30 do not take part in the revolving of the needles and which serve to take up in themselves the rolled mouth pieces 79, which mouth pieces are subsequently pushed outward off the rolling needles 47, 47^a by means 35 of tube shaped pushers 49 each surrounding needle 47, or 47^a within the respective sleeve 48 (Figs. 16-18). The pushers 49 are provided each with a prong 50 movable along its sleeve 48 in a slot 51 to guide the reciprocating motion of the pusher 49. The pushers 49 are reciprocally operated from the driving shaft 52 by means of a drum 53 provided with a curved slot 54 in which moves a finger 55 projecting from the support 55^a for the pushers 49, which finger 55 during the revolving of the drum 53 follows the slot 54 and thus moves the support 55^a with the pushers 49 forward and rearward with reference to the needles 47, 47^a.
- 40 In front of the sleeves 48 there is a wheel 57 journaled in bearings 58^a. This wheel has its entire circumference provided with axial corrugations 58 for the reception and transportation of the cigarette casings 80, which are supplied to the wheel 57 from the cigarette casing producing machine, not illustrated in the drawings as not belonging to this invention. The wheel 57 is made to revolve intermittently from the shaft 52 by 45 means of a ratchet mechanism of which merely the ratchet wheel 57^a is illustrated in the drawing, and by which mechanism the wheel 57 is revolved a distance corresponding to the double pitch of the corrugations 58.
- In front of each rolling needle 47, 47^a is provided a plunger 59 reciprocating to and from the respective needles in the direction of their length by means of which, the cigarette casings 80, guided in the corrugations 58, are moved ahead toward the corresponding sleeve 48. The sleeves 48 may be somewhat tapered at the end, so that the cigarette casing 80, which is manufactured of very thin paper, can be expanded a little 50 at the end to facilitate the insertion of the mouth piece 79 therein. The plungers 59 are arranged on a support 62 from which descends a finger 63 movable in a curved slot 61 on the circumference of a drum 60 keyed on the driving shaft 52, whereby the plungers receive their reciprocating movements when the shaft 52 revolves. In the support 62 there are further mounted two rods 64 parallel to the plungers 59 and 60 spaced apart so far that, when pushing the plungers ahead toward the wheel 57, each plunger 59 as well as each rod 64 moves along one of the corrugations 58 of the wheel 57, which, during this period of the working 65 of the machine is kept at rest as it is not actuated this moment from the ratchet mechanism 57^a. The rods 64 are tapered or rounded at their ends and serve to push the inner end of the mouth piece paper spiral 60 somewhat rearward in order to produce the small space for receiving a portion of the tobacco also in the mouth piece proper as mentioned before. For this reason the rods 64 must be applied on that side of the 70 plungers 59 to which the upper portion of the wheel 57 moves during its revolving, so that the rods do not actuate the mouthpieces before these have been inserted into their cigarette casings 80. To hold the 75 mouthpieces 79 firmly during this inward pushing of their ends there is provided a clamping device 70 (Figs. 12, 13) guided up and down in a stanchion 71 having a lug 72 in which moves a prong 73 projecting from the 80 clamping device 70 and surrounded by a spring 74 which pushes the clamping device 70 downwardly against the mouth piece in the wheel corrugation 58 (dotted lines in Fig. 12). The clamping device 70 is operated by double lever 75 pivoted about a fulcrum 76 and actuated by a cam disk 77 on the shaft 4.
- The machine is driven by means of a belt on a pulley 65 on the shaft 52 beyond which 85 is provided a loose pulley 66 as usual for stopping the working of the machine.
- The machine operates as follows:
- The paper strip 1 is fed along between the rollers 2 and 3 by means of the longer rough portion 10 of roller 2 till the foremost (square) edge of the strip has arrived just below the feeding implement 43 above the horizontally positioned bridge 25 as illustrated in Fig. 21 as well as in view I of 90

Fig. 25. In exactly this moment the entire rough portion 10 of roller 2 has released the paper strip 1 and the forward moving of the strip is interrupted and the pair of scissors or knives 15 cut off a paper piece *a* long enough to form the mouth piece 79. Thus one end of the piece of paper is made square while the other end is tapered. The rough portion 10, as may be understood, must be coextensive in length with the paper piece *a*. Figs. 22 and view II of Fig. 25 illustrate the last mentioned view when the knives 15 cut through the paper strip 1. The table 17 hitherto has maintained its uppermost position with its upper surface in a plane with the upper surface of bridge 25, but immediately after the knives 15 have cut off the piece *a* the table 17 descends to the lowermost position, whereby its upper surface is directed downwardly toward the slot in the adjacent rolling needle 47 (Fig. 20). In the mean time the smaller rough portion 11 of the roller 2 has reached the contact with the yet uncut length of the paper strip 1 and feeds the strip forward so far, that the tapered end thereof arrives by means of the slot 48^a in the sleeve 48 into the slot in the adjacent rolling needle 47 (Figs. 23 and view III of Fig. 25). Now as the smaller rough portion 11 released the paper strip 1, the movement of the strip accordingly ceases, and the "square" pair of scissors or knives 14 cut off the paper piece *b*, which is of exactly the same length as the paper piece *a* but of a reverse position, so that its foremost end is tapered, while the rear end is square (Fig. 24 and view IV of Fig. 25). The pinions 56^a of the rolling needles 47, 47^a in this view have come into coöperation with the toothed portion of wheel 56 and thus make the needle 47 revolve and roll up the paper piece *b* to form a mouthpiece 79. At the same time however, the bridge 25 gets turned around 180 degrees into its reverse horizontal position, so that the upper side of the bridge 25 situated paper piece *a* now will be found on the under side of said bridge, where it is kept from falling down by means of guides 90. The table 17 is also raised to its upper position, the longer rough portion 10 of roller 2 once more reaches the paper strip 1, whereupon a fresh portion of the strip is fed forward up on the now existing upper side of the bridge 25 such as illustrated in Fig. 21 and view V of Fig. 25. The "oblique" knives 15 now cut off another paper piece *a'* with a square fore end and an oblique after end, just as in view II of Fig. 25 and here illustrated by Fig. 22 and view VI of Fig. 25. The feeding implement 43 pulls this paper piece ahead, in the same direction as the feeding direction of the uncut paper strip 1, to the remote end of the bridge 25 as shown in

Fig. 23 and view VII. In the mean time the lower feeding implement 44 has caught the paper piece *a* on the underside of the bridge 25 and moves it along the bridge, but now in the reverse direction with reference 70 to the beforementioned feeding course, till the tapered edge of this paper piece has arrived into the slot in the rolling needle 47^a.

During this period the table 17 has descended, the "square" knives 14 as in view IV of Fig. 25 cut off a fresh piece *b'*, the tapered edge of which has previously been inserted into the rolling needle 47 by means of the smaller rough portion 11 of 80 roller 2, and two paper pieces, viz. *a* and *b'* are rolled up to mouth pieces 79, each by its own rolling needle 47^a and 47 respectively, the table 17 ascends, a further piece of the paper strip 1 gets moved ahead, the 85 foremost portion thereof is cut off, the bridge 25 turns about, and so on.

In the above there have been demonstrated eight different operating moments, though during the ordinary working of the machine merely the four last mentioned stages (views V-VIII of Fig. 25) occur, while the four first mentioned stages (I-IV Fig. 25) take place only at the every new starting of the operation. 95

Having thus described my said invention and how it is to be performed, what I claim and want to protect by Letters Patent is:

1. A machine for making tubes comprising rotatable needles, movable tables associated with said needles, means for feeding material to said needles, means for cutting said material, and means for moving said tables to cause said material to enter said needles. 100

2. A machine for making tubes comprising a movable table, means for moving a strip of material across said table, a needle located adjacent said table, means for moving said table during movement of said material to cause the latter to enter the eye of said needle. 110

3. A machine for making tubes comprising a hinged table, a rotatable table, means for moving strips of material over said tables, needles associated with said tables, and means for moving said tables during moving of said strips to cause said strips to enter the eyes of said needles. 115

4. A machine for making tubes comprising a hinged table, a rotatable table spaced from said hinged table, rolling needles interposed between said tables, means for introducing a strip of material onto each of said tables, means for moving said strips toward each other, means for moving said tables during movement of said strips to cause said strips to enter said needles, and means for rotating said needles. 120

5. A machine for making tubes comprising 130

ing a plurality of rotatable needles, means for introducing strips of material into the eyes of said needles, casings for said needles and means for rotating said needles in different directions.

6. A machine for making tubes comprising a rotatable needle, a movable table having a working surface normally out of alignment with the eye of said needle, means for moving a strip of material over the working surface of said table and in the direction of said needle, and means for moving said table to cause its working surface to align with the eye of said needle during movement of the strip.

7. A machine for making tubes comprising a rotatable needle, a rotatable table having a working surface normally disaligned with the eye of said needle and means for inverting said table to cause the working surface of said table to align with the eye of said needle.

8. A machine for making mouthpieces for cigarette casings of a continuous strip of paper comprising a feeding device for the strip of paper, means for cutting off sections of paper, each of said sections having one end tapered, reversely disposed means for forming said sections into tubes, and means for conveying said sections from said feeding means in such a manner that the tapered ends of said sections will be presented to said forming means.

9. A machine for making tubes comprising a pair of spaced tables, needles between the tables, means for feeding a continuous strip of paper to one of said tables, means for cutting said strip, means for feeding said cut portion to the other of said tables, means for cutting a second portion of said strip on the first mentioned table, means for moving one of said portions into one of said needles, means for moving the other of said portions from the second table into the other of said needles, means for rotating said needles.

10. A machine for making tubes comprising a pair of spaced tables, needles between the tables, means for feeding a continuous strip of paper to one of said tables, means for cutting said strip, means for feeding said cut portion to the other of said tables, means for cutting a second portion of said strip on the first mentioned table, means for moving one of said portions into one of said needles, means for moving the first mentioned cut portions from the second table into the other of said needles, means for rotating said needles, a drum having peripheral pockets formed therein, and means for intermittently revolving said drum a predetermined distance whereby said corrugations will successively register momentarily with said needle.

65 11. A machine for making tubes comprising

ing means for forming sections of material, each having a tapered end, from a single length of material, means for simultaneously making tubes of two successive sections, and means for inserting each of said sections into cigarette casings.

12. In combination, mouthpiece forming members, supporting rods adapted to have cigarette casings mounted thereon, plunger rods and mechanism for actuating said supporting rods and said members to insert the mouthpieces into the cigarette casing and to withdraw said supporting rod and insert said plunger rod for locking the mouthpiece and casing together.

13. A cigarette assembling machine comprising means for supporting a mouthpiece, means for supporting a casing, means for actuating both of said means to effect an interfitting of the ends of said mouthpiece and said casing.

14. A machine for making mouthpieces for cigarettes comprising means for feeding a continuous strip of paper, means for cutting the paper into two strips, each strip having a tapered end and a square end, means for turning one strip 180° about an axis parallel to the direction in which the paper is fed, needles arranged to receive the tapered ends of the strips, and means for rotating said needles to form said strips into mouthpieces.

15. A machine for making mouthpieces for cigarettes comprising means for feeding a continuous strip of paper, means for cutting the paper into two strips, each strip having a tapered end and a square end, needles for forming said strips into mouthpieces, means for turning one strip 180° about an axis parallel to the direction in which the paper is being fed to present the tapered ends of the strips to one of said needles, a movable table for presenting the tapered ends of the other strip to the other needle, and means for rotating said needles.

16. A machine for making mouthpieces for cigarettes comprising means for feeding a continuous strip of paper, means for cutting the paper into two strips, each strip having a tapered end and a square end, needles for forming said strips into mouthpieces, a table for receiving one of said strips and presenting the tapered end thereof to one of said needles, means for intermittently rotating said table about an axis parallel to the direction in which said strip of paper is being fed, and a vertical movable table for receiving the other strip and presenting the tapered end thereof to the other needle.

17. A machine for making mouthpieces for cigarettes comprising means for feeding a continuous strip of paper, means for cutting the paper into two strips, each strip having a tapered end and a square end,

needles for forming said strips into mouthpieces, a table for receiving one of said strips and presenting the tapered end thereof to one of said needles, means for rotating said table about an axis parallel to the direction in which said strip of paper is being fed, means for automatically checking said table when one or the other of the working surfaces stand horizontally, means for releasing 10 said table after a predetermined interval, and a vertical, movable table for receiving the other strip and presenting the tapered end thereof to the other needle.

18. A machine for making mouthpieces 15 for cigarettes comprising means for feeding a continuous strip of paper, means for cutting the paper into two strips, each strip having a tapered end and a square end, needles for forming said strips into mouth- 20 pieces, means for rotating said needles intermittently and in opposite directions, a table for receiving one of said strips and presenting the tapered end thereof to one of said needles, means for intermittently rotating 25 said table about an axis parallel to the direction in which the strip of paper is being fed, and a vertical, movable table for receiving the other strip and presenting the tapered end thereof to the other needle.

30 19. A machine for making mouthpieces for cigarettes comprising two feeding rollers arranged one above the other and having abrasive portions on the surfaces thereof, elastic means for biasing said rollers toward 35 each other, said rollers being adapted to feed a continuous strip of paper, means for cutting the paper into two strips, each strip having a tapered end and a square end, means for turning one strip 180° about an 40 axis parallel to the direction in which the paper is being fed, needles arranged to receive the tapered ends of the strips, and means for rotating said needles to form said strips into mouthpieces.

45 20. A machine for making mouthpieces for cigarettes comprising means for feeding a continuous strip of paper, means for cutting the paper into two strips, each strip having a tapered end and a square end, 50 means for turning one strip 180° about an axis parallel to the direction in which said paper is being fed, needles arranged to receive the tapered ends of the strips, means for feeding said strips to said needles, and means for rotating said needles to form said strips into mouthpieces.

60 21. A machine for making mouthpieces for cigarettes comprising means for feeding a continuous strip of paper, means for cutting the paper into two strips, each strip having a tapered end and a square end, 65 means for turning one strip 180° about an axis parallel to the direction in which said paper is being fed, needles arranged to receive the tapered ends of the strips, means

for rotating said needles, a drum having axial corrugations on the entire periphery thereof, and means for intermittently rotating said drum so that one of the corrugations will be momentarily alined with one 70 of said needles.

22. A machine for making mouthpieces 75 for cigarettes comprising means for feeding a continuous strip of paper, means for cutting the paper into two strips, each strip having a tapered end and a square end, means for turning one strip 180° about an axis parallel to the direction in which said paper is being fed, needles arranged to receive the tapered ends of the strips, means 80 for rotating said needles, and means for feeding the strip which is adapted to be turned, in a direction reverse to the feeding of the continuous strip of paper.

23. A machine for making mouthpieces 85 for cigarettes comprising means for feeding a continuous strip of paper, means for cutting the paper into two strips, each strip having a tapered end and a square end, needles arranged to receive the tapered ends 90 of the strips, and sleeves surrounding the needles for guiding the mouthpieces while being rolled and having axial slots to receive and guide the strips into their respective needles. 95

24. A machine for making mouthpieces for cigarettes comprising means for feeding a continuous strip of paper, means for cutting the paper into two strips, each strip having a tapered end and a square end, means for turning one strip 180° about an axis parallel to the direction in which the paper is being fed, needles arranged to receive the tapered ends of the strips, sleeves surrounding said needles for guiding the 100 mouthpieces when being rolled and having axial slots to receive and guide the strips into their respective needles, conical ends formed on each of said sleeves and projecting beyond said needles, means for forcing 110 a cigarette casing against said conical end, and means for moving a finished mouthpiece from the needle into said casing while the latter is in engagement with said conical end. 115

25. A machine for making mouthpieces 120 for cigarettes comprising means for feeding a continuous strip of paper, means for cutting the paper into two strips, each strip having a tapered end and a square end, means for turning one strip 180° about an axis parallel to the direction in which said paper is being fed, needles arranged to receive the tapered ends of the strips, sleeves surrounding the needles for guiding the 125 mouthpieces while being rolled and having axial slots to receive and guide the strips to their respective needles, means for inserting each finished mouthpiece into a cigarette casing, and means for slightly forcing inwardly one end of each mouth- 130

piece to form a space between the casing and mouthpiece to receive a portion of the tobacco when filling the casing.

26. A machine for making mouthpieces for cigarettes comprising means for feeding a continuous strip of paper, means for cutting the paper into two strips, each strip having a tapered end and a square end, means for turning one strip 180° about an axis parallel to the direction in which said paper is being fed, needles arranged to receive the tapered ends of the strips, sleeves surrounding the needles for guiding the mouthpieces while being rolled and having axial slots to receive and guide the strips to their respective needles, means for inserting each finished mouthpiece into a cigarette casing, means for slightly forcing inwardly one end of each mouthpiece to form a space between the casing and mouthpiece to receive a portion of the tobacco when filling the casing, said means comprising parallel spaced rods formed with tapered ends, and means for moving said rods to engage and force the inner end of the mouthpieces rearwardly into said casing.

27. A machine for making mouthpieces for cigarettes comprising means for feeding a continuous strip of paper, means for

cutting the paper into two strips, each strip 30 having a tapered end and a square end, means for turning one strip 180° about an axis parallel to the direction in which said paper is being fed, needles arranged to receive the tapered ends of the strips, sleeves 35 surrounding the needles for guiding the mouthpieces while being rolled and having axial slots to receive and guide the strips to their respective needles, means for inserting each finished mouthpiece into a cigarette 40 casing, means for slightly forcing inwardly one end of each mouthpiece to form a space between the casing and mouthpiece to receive a portion of the tobacco when filling the casing, said means comprising parallel 45 spaced rods formed with tapered ends, means for moving said rods to engage and force the inner end of the mouthpiece rearwardly into said casing, and means for clamping the casing during the last-mentioned operation.

In testimony whereof I affix my signature in presence of two witnesses.

OSCAR SANDBERG.
